CLAIM

The ornamental design for an electrical connector assembly,
as shown and described.

DESCRIPTION

FIG. 1 is a front perspective view of the electrical connector assembly, in accordance with the present design;

FIG. 2 is a front perspective view thereof, from a different angle;

FIG. 3 is right side elevational view thereof;

FIG. 4 is a top plan view thereof;

FIG. 5 is a bottom plan view thereof;

FIG. 6 is a front elevational view thereof;

FIG. 7 is a front perspective view of a socket arrangement
of the electrical connector assembly of FIG. 1;

FIG. 8 is a bottom perspective view thereof;

FIG. 9 is a bottom plan view thereof;

FIG. 10 is a rear elevational view thereof;

FIG. 11 is a top, front perspective view of the plug arrangement
of the electrical connector assembly of FIG. 1;

FIG. 12 is a bottom perspective view thereof;

FIG. 13 is right side elevational view thereof;

FIG. 14 is a rear elevational view thereof; and,

FIG. 15 is front elevational view thereof.

The drawings include break lines which represent a symbolic break in length of the electrical connector assembly
and form no part of the claimed design. The dash-dash
broken lines shown in the drawings illustrate portions of the
electrical connector assembly that form no part of the
